UNITED STATES PATENT OFFICE

JOHN C. HANNA, OF CHICAGO, ILLINOIS

RIVETER

Application filed July 5, 1924. Serial No. 724,232.

This invention relates to a new and improved riveter and more particularly to a riveter of this character in which a bell crank lever carries a rolling pin operating 5 against an irregular cam surface.

Riveters of this type comprise a pair of jaw members pivotally connected together and having jaws adapted to engage the opposite ends of a rivet and to properly form it to rivet it in place. The movement of the jaws is caused by the action of a lever carried by one of the jaw members and provided with means engaging a cam surface carried by the other jaw member. As the 10 resistance of the rivet to the deformation caused by the riveting action varies during the action, it is desirable to provide a non-uniform closing movement of the riveting jaws so as to give an ideal pressure stroke of 15 the riveting jaws. This ideal pressure stroke approximates the deformation resistance of the rivet which is minimum at beginning and maximum at completion. The pressure must always exceed the rivet resistance. 20 This excess should be the minimum which will result in deformation at practical speed, as any more available pressure entails the use of superfluous power. It is further desired that the pressure stroke 25 shall attain to maximum near its end and from this point of attainment to the end pressure shall be uniform. Various forms of toggles will develop a pressure stroke somewhat similar to what is desired in the 30 non-uniform part of the ideal pressure stroke. Simple levers will develop what is desired in the uniform part of the ideal stroke near its end. The ideal stroke is unlike the stroke produced by either toggle 35 or lever, but is graduated from a minimum pressure at start to a maximum pressure at about seven-eighths of its length, this maximum being maintained for the remaining one-eighth of length. This latter uniform 40 pressure zone of stroke is desirable as com-

pensation for irregularities in length of stroke as found in practice and as definite determination of the pressure on each rivet and the strains in the riveting mechanism.

It is an object of the present invention to 50 provide a lever operated riveter having a lever operating between a pivoted center upon one jaw member and a cam surface of irregular contour carried by the other jaw member whereby an ideal pressure stroke is 55 secured.

It is a further object to provide a riveter of this type in which the cam engaging element carried by the lever is a rolling pin 60 preferably mounted upon a roller bearing in the lever.

It is an additional object to provide construction of this type in which the rolling pin engages spaced cam members located 65 upon opposite sides of the lever.

It is also an object to provide a riveter of this type in which the lever is pivotally mounted upon roller bearings carried upon one of the jaw members.

Other and further objects will appear as 70 the description proceeds.

I have illustrated a preferred embodiment of my invention in the accompanying drawings, in which—

Figure 1 is a side elevation of the riveter, 75 portions being broken away in order to show the construction;

Figure 2 is a horizontal section taken on line 2—2 of Figure 1;

Figure 3 is a view of Figure 1 as seen 80 from the right; and

Figure 4 is a section taken on line 4—4 of Figure 1.

The riveter comprises the upper jaw member 11 and lower jaw member 12 which are 85 pivotally connected together by the pivot pin 13. The riveter is supported by the hangers 14 which engage the pivot pin 13 and are connected to the bail 15. The hangers 14 are secured by means of the stud 16 90

at the proper angle to balance the riveter about the bail. The upper riveting die 17 is secured in the upper jaw member 11 by means of the sleeve 18 in which the die may be adjusted by means of the thread 19. The lower die 20 is secured to the lower jaw in alignment with the upper die.

The lever 21 is pivotally supported in the rear end 22 of the upper jaw member 11 upon the rollers 23 bearing upon pin 24. The upper end 25 of the lever is bifurcated and has secured thereto the piston rod 26 by means of pin 26'. The piston rod 26 is secured to piston 27 operating in cylinder 28. The cylinder 28 is pivotally supported upon trunnions 29 carried in supporting lugs 30 extending upwardly from the upper jaw member 11. Supported upon the end of the cylinder is the valve mechanism 31 which forms no part of this invention and which need not be described in detail. This mechanism is adapted to selectively introduce fluid under pressure into the right hand end of the cylinder through pipe 32 or into the left hand end of the cylinder through pipe 33.

The lower end of the lever carries the rolling pin 34 upon the roller bearing 35. This pin 34 extends upon both sides of the lever and engages the upper cam surfaces of the cam members 36 and 37. The guide disks 38 and 39 are secured to the opposite ends of the rolling pin 34 and engage the outer face of the cam members. As shown in Figure 1, the cam members are secured to the lower jaw member by means of bolts 40.

The lower end of the return rod 41 passes through the block 42 secured to the lower jaw member by the bracket 42'. The lower end of the return rod carries the lock nut assembly 43 which limits its upward movement. The upper portion of the return rod passes through an upper block 44 pivotally connected by means of bolt 44' to the return rod bracket 45. This bracket 45 is secured to the lever by means of bolts 46. The compression spring 47 surrounds the upper end of the return rod, its lower end engaging the upper return rod block and its upper end engaging the lock nut assembly 48.

The riveter is shown in Figure 1 with the riveting dies closed down upon the rivet. The lever is at its limit of counterclockwise movement. The cam blocks 36 and 37 are held against the rolling pin 34 by means of the return rod 41 and its associated parts. The spring 47 yieldingly supports the upper end of the return rod from the upper return rod block which is secured to the return rod block bracket which latter is secured to the lever. The lower end of the return rod thus is drawn upwardly against the lower return rod block.

When it is desired to open the jaws the

fluid under pressure is introduced into the left end of the cylinder 28 by proper operation of the valve 31. This operation it will be understood opens the right hand end to the atmosphere through pipe 32. 70 This fluid under pressure causes the piston 27 to move to the right carrying with it the piston rod 26. Through the action of the piston rod with upper portion 25 of the lever, the lever is rotated about its 75 pivot in the clockwise direction. As the lever moves in this direction, the cam surfaces 36 and 37 are maintained in contact with the rolling pin 34. These surfaces are of such contour that during this clockwise 80 movement the rear end of the lower jaw approaches the rear end of the upper jaw. Consequently the riveting dies are separated.

When another rivet to be operated upon 85 is placed between the dies the lever is caused to move in the counter-clockwise direction by introducing fluid under pressure through pipe 32 into the right end of the cylinder 28 by means of suitable operation 90 of valve 31. Due to the formation of the cam surfaces the roller 34 rolling down them causes the rear end of the jaw members to be separated and the riveting dies to approach each other and have a riveting 95 action upon the rivet located between them. Due to the particular formation of the cam surfaces the closing movement of the jaws is not uniform but affords an ideal pressure stroke of the riveting jaws. 100

It is to be understood that the particular construction illustrated has been shown by way of example and I contemplate such changes and modifications to meet varying conditions as may come within the scope of 105 the appended claims.

I claim:

1. In a riveter, a pair of pivoted jaw members, a lever pivoted to one jaw member, a pair of spaced parallel cam surfaces 110 carried by the other jaw member, and engaging means extending on opposite sides of the lever to engage the cam surfaces whereby the jaws are caused to move together.

2. In a riveter, a pair of jaw members pivoted together at an intermediate point, a lever pivoted to one jaw member, a cam carried by the other jaw member, said lever carrying means adapted to engage the cam, 120 said lever having a portion extending above the first jaw member, and an operating cylinder and piston pivotally supported from the first jaw member, said piston being connected to the upper end of the lever. 125

3. In a riveter, a pair of jaw members pivoted together at an intermediate point, a lever pivoted to one jaw member, a cam carried by the other jaw member, said lever carrying means adapted to engage the cam, 130

said lever having a portion extending away from the first jaw member, an operating cylinder and piston carried by the first jaw member, said piston being connected to the lever portion for operating the riveter, and means to normally urge the lever and cam carrying ends of the lever together, said means comprising a rod pivotally connected to one jaw and extending through a block pivotally supported by the upper jaw, a spring surrounding the rod above said jaw above the block and adjustable bearing means on the upper end of the rod.

Signed at Chicago, Illinois, this 28th day
15 of June, 1924.

JOHN C. HANNA.
